COOKING RANGE

Albert E. Smallwood, Taunton, Mass., assignor to
 Servel, Inc., New York, N. Y., a corporation of
 Delaware

Application December 30, 1944, Serial No. 570,687

4 Claims. (Cl. 126—39)

1

My invention relates to gas ranges and more particularly to arranging and supporting top burners in the cooking top of domestic gas ranges.

With domestic gas ranges it is necessary that the top burners and burner accessories be removed periodically so that they may be cleaned. This is necessitated by spillovers from cooking utensils on the top burners.

It is also necessary that the top burners be readily removed so as to clean the inside of the burner compartment. For this reason, it is desirable that the top burners be supported in such manner that both the burners and their supports may be readily removed from the burner compartment so as to leave this compartment relatively free of obstructions, sharp angular members, or the like, which would otherwise hinder the removal of accumulated smudge or grease from the burner compartment.

On the other hand, it is necessary and desirable that the top burners and burner accessories be firmly secured in the cooking top so that the burners are properly centered at all times and so that the burner grates, for example, are steady and level, thereby eliminating the tipping over of small cooking utensils.

It is further desirable that the top burner flash tubes, which ignite the several burners from a constantly-burning pilot or the like, be definitely and securely located with respect to the burners and to the pilot.

It is, therefore, an object of my invention to provide a gas range wherein the top burners and burner supports may be readily removed and assembled for cleaning.

It is a further object of my invention to provide a gas range wherein, when the top burners and burner supports are removed, the interior of the burner compartment is free of obstructions which would otherwise hinder the cleaning of said compartment.

It is a further object of my invention to provide a gas range wherein the top burners and burner accessories, while readily removable, are securely and firmly mounted in the cooking top.

It is a still further object of my invention to provide a gas range wherein the top burner flash tubes are secured and properly located between the igniter and the several burners which they serve.

My invention, together with its objects and advantages, is more fully set forth in the following description and accompanying drawing, wherein like reference characters are used to designate like parts throughout, and wherein:

2

Fig. 1 is a top plan view of a gas range incorporating one embodiment of my invention;

Fig. 2 is a vertical sectional view taken substantially on line 2—2 of Fig. 1;

Fig. 3 is an exploded view, partly in section, of one of my improved burner assemblies;

Fig. 4 is a partial top plan view of the cooking top illustrated in Fig. 1; and

Fig. 5 is a top plan view of one of my improved burner supporting rings and attached flash tube.

Referring now to the drawings, 10 designates generally the cooking top of a domestic gas range. This cooking top includes a top or working panel 11 provided with four circular openings 12 located longitudinally and in line across the rear portion of said panel. Each of openings 12 is adapted to receive a top burner assembly designated generally by reference characters 13, 13', 13'' and 13'''. A back guard 14 projects upwardly from panel 11 and is provided with ventilating louvers 15. The front of the cooking top is formed with an inclined panel or console 16 adapted to receive and support gas valves 17 for the top burners. This console also supports the gas valves (not shown) and control dials 18 and 19 for the oven and broiler (not shown). Each of the gas valves is equipped with a manually-operable button or handle 20 and each valve is connected to a gas manifold 21. A gas tube 22 is connected at one end to each of the gas valves 17 and is provided on its opposite end with a nozzle 23. Nozzles 23 are supported by an elongate bracket or angle member 24. Bracket 24, which is supported at each end from side panels (not shown), is located in front of the top burners in a burner compartment 25. This bracket supports all of the gas conduits and aids in supporting the top burners, as will be described more in detail hereinafter. In other words, bottom panel 26 of compartment 25, as shown in Fig. 2, is free of conduits, supports or obstructions of any kind which might hinder the cleaning of said panel. A pair of pilot burners 27 (shown in broken lines in Fig. 1) are located in compartment 25 and are supplied with

gas from manifold 21 by conduits 28, which conduits are supported by bracket 24. Pilots 27 are supported by brackets (not shown) which are generally similar to bracket 24 and which support said pilots clear of bottom panel 26.

Top burner assemblies 13 and 13'', which are interchangeable, have a mixing tube projecting from the left side and a flash tube from the right side thereof, as viewed in Fig. 1. Top burner assemblies 13' and 13''', which are interchangeable, have a mixing tube projecting from the

right side and a flash tube from the left side thereof, as viewed in Fig. 1. Top burner assemblies 13 and 13'', which are interchangeable, have a mixing tube projecting from the left side and a flash tube from the right side thereof, as viewed in Fig. 1. Top burner assemblies 13' and 13''', which are interchangeable, have a mixing tube projecting from the

right side and a flash tube from the left side thereof, as viewed in Fig. 1. Top burner assemblies 13 and 13'', which are interchangeable, have a mixing tube projecting from the left side and a flash tube from the right side thereof, as viewed in Fig. 1. Top burner assemblies 13' and 13''', which are interchangeable, have a mixing tube projecting from the

right side and a flash tube from the left side thereof, as viewed in Fig. 1. Top burner assemblies 13 and 13'', which are interchangeable, have a mixing tube projecting from the left side and a flash tube from the right side thereof, as viewed in Fig. 1. Top burner assemblies 13' and 13''', which are interchangeable, have a mixing tube projecting from the

right side and a flash tube from the left side thereof, as viewed in Fig. 1. Top burner assemblies 13 and 13'', which are interchangeable, have a mixing tube projecting from the left side and a flash tube from the right side thereof, as viewed in Fig. 1. Top burner assemblies 13' and 13''', which are interchangeable, have a mixing tube projecting from the

right side and a flash tube from the left side thereof. Otherwise, each of the top burner assemblies is substantially identical; therefore, a description of one assembly will suffice for the four. Referring now to Figs. 2-4, each of the openings 12 in top panel 11 is bound by a downwardly-projecting flange 29 which is formed with three unequally-spaced ears 30. Ears 30 are each provided with openings to receive small locating pins 31 which pins are screw threaded on their lower ends and are attached to the ears 30 as by a nut as shown in Fig. 2 of the drawing. A ring-shaped supporting member 32, made of an angle member and provided with three unequally-spaced openings 33, is supported by ears 30 with locating pins 31 projecting into openings 33. The spacing of the openings in supporting rings 32 coincide with the spacing of locating pins 31 so as to properly position the burner assemblies within the cooking top openings. A stirrup 34 is welded or otherwise secured to supporting ring 32, as at 35. Stirrup 34 is provided with two openings 36 and 37 adapted to receive centering or locating lugs 38 and 39, respectively, of a gas burner 40. Gas burner 40 includes a main burner portion 41, a simmer burner portion 42 (see Fig. 1), a mixing tube 43, and an air shutter 44. Air shutter 44 is provided with a central opening 45 adapted to snugly receive gas nozzle 23, thereby providing a third support for the burner. A port 46 is provided in the periphery of burner 40 and is adapted to supply a jet of gas to a flash tube 47. Flash tube 47 is welded or otherwise permanently secured to supporting ring 32 in such manner that when said ring is properly positioned on locating pins 31, the flash tube will be properly positioned between the port 46 in the periphery of the burner and one of the pilot burners 21, as shown in Fig. 1. The unequal spacing of ears 30 and of openings 33 in the supporting ring 32 insures that the supporting ring is properly positioned within the cooking top opening, whereby the flash tube 47 will be properly positioned with respect to the pilot burner and the top burner will be properly positioned within the cooking top opening.

An annular heat reflector 48 fits around the upper portion of burner 40 and is supported on top panel 11 by a peripheral flange 49. Flange 49 is provided with three equally-spaced semi-circular notches 50 in its periphery which are adapted to register with three equally-spaced small openings 51 in top panel 11 in the immediate vicinity of the flanged openings 12 of said top panel. A circular grate 52, provided with six tines, fits over burner 40 so as to support cooking utensils above said burner. Alternate tines of grate 52 project beyond the periphery of the circular portion of the grate and are each provided with lugs 53. Lugs 53 are adapted to pass through the three equally-spaced notches 50 of reflector 48 and into the three equally-spaced openings 51 in the top panel, thereby securing both the reflector and the grate in proper position relative to the burner. Each of the reflectors 48 is substantially identical and therefore interchangeable. Also, the grates 52 are substantially identical and interchangeable.

Bottom panel 26 is provided with four embossed portions or bosses 54, one located centrally beneath each of the top openings 12, and each adapted to receive and locate an individual drip pan 55.

In operation, when it is desired to clean the burner assemblies, the drip pans and/or the burner compartment, the burner assemblies are

readily removed by first removing the grates, then the reflectors, then the separate burners, then the burner supporting rings, and finally the individual drip pans, thus leaving the panel 5 26 free of all obstructions which might hinder the cleaning of said panel. The individual drip pans and each of the elements that make up the burner assemblies are of such size that they may be washed along with the usual household cooking utensils. After the different elements have 10 been washed, they are replaced in the reverse order of their removal. It is to be noted that when the supporting rings and attached flash tubes are returned to their position in the cooking top that the flash tubes are definitely and correctly positioned relative to the pilots. It is 15 also to be noted that the three-point suspension, supporting and locating arrangement of the supporting rings, the burners, the reflectors and the grates insures proper location and centering of each of these elements at all times.

Various changes and modifications may be made within the scope of the invention, as set forth in the following claims.

25 What I claim is:

1. In a gas range, a top panel provided with a top burner opening, a supporting ring removably supported at three points by said top panel, a gas burner, means supporting said gas burner at three 30 points, a heat reflector surrounding said gas burner, a grate located above said gas burner, and means in said top panel, said reflector and said grate whereby said reflector and said grate are supported and centered at three points relative to said top burner and burner opening.

2. In a gas range, a top panel provided with a top burner opening, a supporting ring removably supported at three points by said top panel, a gas burner, a gas supply conduit, means supporting 40 said gas burner at two points on said supporting ring and at a third point on said gas supply conduit, a heat reflector surrounding said gas burner, a grate located above said gas burner, and means in said top panel, said reflector and said grate 45 whereby said reflector and said grate are supported and centered at three points relative to said top burner.

3. In a gas range, a top panel provided with a relatively large top burner opening and three relatively small openings equally spaced around said large opening, a supporting ring removably supported in said large opening at three points by said top panel, a gas burner, a gas supply conduit for said burner supported beneath said top panel, means supporting said gas burner at two points by said supporting ring and at a third point by said gas supply conduit, an annular heat reflector surrounding said gas burner provided with three 55 equally-spaced semi-circular notches in the periphery thereof, and a circular grate located above said gas burner provided with three equally-spaced lugs projecting downward from the periphery thereof adapted to pass through the three notches in said heat reflector and into the three 60 equally-spaced openings in said top panel.

4. In a gas range, a cooking top having an opening bound by a downward projecting flange, a plurality of ears projecting inward from said flange, a pilot burner beneath said cooking top, 70 and a removable assembly comprising a ring resting on said ears, a stirrup secured at its two ends to opposite sides of said ring, a gas burner resting in said stirrup and a flash tube fixed on said ring, said assembly being provided with locating devices so that the burner is central of the open-

ing in the cooking top and the flash tube has one end adjacent said pilot burner and the other end adjacent said gas burner, and said locating devices comprise a pin on each of said supporting ears, the latter being unequally spaced around said flange, said ring having a plurality of openings adapted to match with and fit over said pins and a plurality of lugs on said gas burner adapted to fit into openings provided in said stirrup.
